UNITED STATES PATENT OFFICE.

AUGUST G. SANDMAN, OF BALTIMORE, MARYLAND.

DESIGN FOR A DRAFT-YOKE.

45,241.

Specification for Design.

Patented Feb. 10, 1914.

Application filed October 21, 1913. Serial No. 796,529. Term of patent 14 years.

To all whom it may concern:

Be it known that I, AUGUST G. SANDMAN, a citizen of the United States, residing at Baltimore city, State of Maryland, have invented a new, original, and ornamental Design for Draft-Yokes, of which the following is a specification, reference being had to the accompanying drawing, forming a part thereof.

Figure 1 is a side view in elevation of a

draft yoke showing my new design. Fig. 2 is a top plan view of Fig. 1.

I claim:

The ornamental design for a draft yoke as shown.

AUGUST G. SANDMAN.

Witnesses:

Wm. N. ALLMAN,
C. HERBERT PIND.
